UNITED STATES PATENT OFFICE.

WILLIAM H. C. HIGGINS, JR., OF ORANGE, NEW JERSEY.

CARBURETER.

No. 856,638.

Specification of Letters Patent.

Patented June 11, 1907.

Application filed July 13, 1906. Serial No. 326,021.

REISSUED

To all whom it may concern:

Be it known that I, WILLIAM H. C. HIGGINS, Jr., a citizen of the United States, residing at Orange, in the State of New Jersey, have invented certain new and useful Improvements in Carbureters, of which the following is a specification, reference being had to the accompanying drawings, forming a part thereof.

10 This invention relates particularly to the devices in which the gaseous mixture of hydrocarbon vapor and air for internal combustion engines is formed and by which the volume and the quality of the mixture supplied 15 are regulated. Devices of this character frequently fail to secure satisfactory mixtures under all conditions. Moreover the valves in such devices are sometimes actuated by suction and are controlled more or less by spring 20 tension.

It is the object of this invention to enable a satisfactory explosive mixture to be produced under all varying conditions of engine load and speed, to eliminate the uncertainty 25 in action of suction actuated and spring controlled valves by actuating the valves directly by mechanical means, and generally to improve the construction and operation of devices of the character referred to.

30 The invention will be more fully described hereinafter with reference to the accompanying drawings in which, for purposes of illustration and explanation of the nature of the invention, it is shown as embodied in a convenient and practical structure.

In said drawings Figure 1 is a top view of the improved carbureter, the fuel nozzle being omitted. Fig. 2 is a section on the plane indicated by the line 2—2 of Fig. 1. Fig. 3 35 is a section on the plane indicated by the line 3—3 of Fig. 2.

In the embodiment of the invention illustrated in the drawings the carbureting chamber *a* is formed by a cap or cover *b* suitably secured to the flat wall *c* of a suitable casting *d*. In the wall *c* are formed three ports, one port *e* being provided for the discharge of the combustible mixture to the engine, and two ports *f* and *g* being provided for the admission of air to the chamber *a* to form the combustible mixture with the hydrocarbon which is admitted through a needle valve *h* of ordinary construction, from a constant level hydrocarbon reservoir, not shown. The

ports *e*, *f* and *g* are controlled by valves 55 which move simultaneously, preferably by a plate slide valve *i* which may be actuated by a lever *k*, or other suitable means, from any suitable source of motion, such as the hand of the operator or an engine governor, if one 60 be employed. The valves or valve plate are or is arranged to open the two ports *e* and *f* in like measure or to close them in like measure, but to close the port *g* as the ports *e* and *f* are opened and vice versa. Independent 65 means are provided for regulating the area of the port *g*; said means consisting, in the construction shown, of a shutter *l* arranged to slide longitudinally over the port *g* and to be secured in adjusted position by a thumb nut 70 and bolt *m* co-operating with an ear *n* of the casting *d*.

In explaining the operation of the improved carbureter it will first be assumed that the quantity of fuel vapor derived from the 75 needle valve or other fuel supply nozzle indicated generally at *h* is dependent upon the quantity of hydrocarbon supplied and upon the degree of vacuum in the chamber *a*. The quantity of hydrocarbon supplied is determined in the usual and well known manner by regulation of the valve *h*. The degree of vacuum in the chamber *a*, assuming that the suction of the engine is constant, depends upon the relative area of the discharge port *e* 85 and the air inlet ports *f* and *g*.

If the port *g* is entirely closed by the shutter *l*, so that the movement of the slide valve *i* has no effect on said port, it is obvious that the area of the port *f* for the admission of air 90 will always be proportionate to the area of the port *e* for the delivery of the mixture, port *f* being wide open when the port *e* is wide open and being closed by the movement of the slide valve *i* in the same proportion 95 as the port *e* is closed. When both ports are wide open the engine receives a full charge of air and the valve *h* is then adjusted by hand to admit such a quantity of hydrocarbon as will produce a satisfactory explosive 100 mixture under such conditions, the engine then generating its full power. It will be seen, however, that if through the operation of the lever *k*, by hand or otherwise, when the load is thrown off the engine, the slide 105 valve *i* is shifted to reduce the effective area of the ports *e* and *f* to the same extent, the vacuum in the chamber *a* will remain about

the same as at full load, whereby, since the supply of hydrocarbon remains constant under these conditions while the volume of air is decreased, the mixture would be too rich. 5 On the other hand, if the shutter *l* is withdrawn so as to leave the port *g* wide open, so that it is then opened by the slide valve *i* in proportion to the closing of the ports *e* and *f* by the same movement, the amount of air admitted to the chamber *a* will depend upon the combined effective areas of the ports *f* and *g*. As indicated in Fig. 3 of the drawings, the port *g* is preferably somewhat longer than ports *e* and *f*, although its width is 10 about the same as that of each of the ports *e* and *f*. Furthermore, the shutter *l* is preferably of such length and so adjusted that the port *g* is never closed completely. It will now be understood that when the slide valve 15 *i* is dropped so as to open the ports *e* and *f* wide, it will at the same time close the port *g* completely, establishing the same condition as above described, with the hydrocarbon inlet valve *h* adjusted properly for operating 20 under full load. If, however, the load be thrown off completely the movement of the slide valve *i* will tend to close the ports *e* and *f* and will open the port *g*. When the port *e* is almost closed, allowing very little mixture 25 to pass to the engine, and port *f* is closed to the same degree while port *g* is nearly wide open, the admission of air to the chamber *a* will be much in excess of the withdrawal and the vacuum in the chamber will therefore be 30 much reduced. If the fuel inlet valve *h* is set as for operation under full load, as above described, the engine, under these conditions, will get too little fuel because of the low degree of vacuum. The shutter *l* must, therefore, be adjusted between the two extreme 35 points for ordinary running conditions, so as to reduce to the necessary extent the effective area of the port *g* and thus maintain a proper degree of vacuum in the chamber *a*. 40 The adjustment of the shutter *l* may be determined by trial under varying conditions of operation.

It will be understood that the details of construction and arrangement may be varied 45 to suit different conditions of use and that the invention is not restricted to the precise construction or arrangement shown.

I claim as my invention—

1. A carbureter comprising a mixing chamber provided with a fuel inlet, two air 55 admission ports, and a delivery port, means actuated externally of the carbureter for varying simultaneously the effective area of all of said ports, and independent means also actuated externally of the carbureter for varying the effective area of one of the air admission ports.

2. A carbureter comprising a mixing chamber provided with a fuel inlet, a port for the delivery of the mixture and a plurality 65 of ports for the admission of air, positively actuated means to open and close the delivery port and one of said air ports and positively actuated means to close and open co-ordinately another of said air ports in op- 70 position.

3. A carbureter comprising a mixing chamber provided with a fuel inlet, a delivery port for the mixture, and a plurality of air inlet ports, means to open and close the 75 delivery port and one of the inlet ports, means actuating simultaneously therewith, to close and open another of the inlet ports, and means to adjust the effective area of the last named inlet port. 80

4. A carbureter comprising a mixing chamber provided with a fuel inlet, a port for the delivery of the mixture, and two ports for the inlet of air, and a valve co-operating with said ports to open the delivery 85 port and one of the air ports and simultaneously close the other of the air inlet ports, and vice versa.

5. A carbureter comprising a mixing chamber provided with a fuel inlet, a port for the delivery of the mixture and two ports for the inlet of air, a valve co-operating with said ports to open the delivery port and one of the air ports and simultaneously close the other of the air inlet ports and vice versa, 95 and means to adjust the effective area of the last named inlet port.

This specification signed and witnessed this 7th day of July A. D., 1906.
